UNITED STATES PATENT OFFICE.

ANDREW PLECHER, OF SAVANNAH, GEORGIA.

ELECTRIC-LIGHTING APPARATUS.

SPECIFICATION forming part of Letters Patent No. 625,599, dated May 23, 1899.

Application filed October 4, 1898. Serial No. 692,630. (No model.)

To all whom it may concern:

Be it known that I, ANDREW PLECHER, of Savannah, in the county of Chatham and State of Georgia, have invented a new and useful 5 Improvement in X-Ray-Lighting Apparatus, of which the following is a specification.

My invention is in the nature of an apparatus which is designed to be employed for purposes of special X-ray illumination or for 10 the purposes of general illumination, as electric lamps; and it consists in the peculiar construction and arrangement hereinafter described with reference to the drawings, in which—

15 Figure 1 is a side view of two of the apparatus connected in series as electric lamps. Figs. 2 and 3 are side views, respectively, of two modifications of the same; and Fig. 4 is a sectional view of an induction-coil.

20 Referring to Fig. 1, A' is a Crookes vacuum tube or bulb. C' is an electromagnet sealed tightly within the walls of the vacuum-bulb and having its helix connected to the primary wire B' and bearing on the inner end 25 of its pole the convex plate E, whose surface is to be covered with a substance which fluoresces or shines by the bombardment of the cathode ray. For such purpose I use a substance known on the market as "Christ- 30 aux de Sidot," made by Louis Müller-Unkel, Braunschweig, Germany. Any other equivalent substance may, however, be employed, such as the sulfates and sulfids of calcium, barium, and strontium, or the calcium wol- 35 fromate, (tungstate.) Entering the vacuum-bulb from opposite sides are the cathode-terminals D' D'. These are tightly sealed in the glass, and the external wire with which they connect extends along the line-circuit from 40 one lamp to the next. They are fully insulated and are wrapped around the primary wire B' in the shape of a coil all along the primary wire B' as it extends from one lamp to the next. This forms a sort of greatly- 45 elongated induction-coil between any two lamps. The outer terminals of the primary wire B', B², or B³ are extended to and connected with the opposite poles of a pole-changing dynamo, and the outer terminals of the 50 secondary wire are connected to each other to complete the secondary circuit. The cathode rays as they radiate from the terminals

D' within the bulb are deflected laterally by the influence of the magnet C' and in bombarding the specially - prepared surface E 55 cause the latter to shine with an intense illumination.

Instead of having two cathode-terminals at right-angular position to the magnet C', as in Fig. 1, I may arrange them as in Fig. 2, where 60 one of the terminals of the secondary wire is carried to the core of the magnet, which then becomes a cathode-terminal, or, if desired, both said terminals may be carried to the cores of diametrically-placed electromagnets, 65 as shown at C³ C⁴ in Fig. 3.

As a further modification the end portion of one or both the secondary wires may first be wrapped or laid in coils around the primary coil of the magnet and then extended to the 70 core or pole, as seen in Fig. 4, in which case the magnet becomes an induction-coil C⁵. In this figure, B⁴ is the primary wire, and D⁴ the secondary, which is not only wound around the primary between lamps, but is wound 75 around the primary wire itself as it lies in the helix, the end x being attached to the core and the other end y forming the opposing cathode. When so employed, the electric-lighting apparatus is converted into a novel 80 form of X-ray apparatus. It is known that a secondary current passing through a vacuum-tube is influenced by a magnet in regard to direction as well as in regard to its light-giving properties. Therefore in placing a 85 magnet at each pole, or rather in making the secondary current from a pole-changing dynamo to traverse the cores of the two magnets, then, according to known facts, the resistance in the vacuum-tube becomes considerably 90 less and the invisible rays are turned into white light.

Having thus described my invention, what I claim as new, and desire to secure by Letters Patent, is—

1. An electric lamp comprising a vacuum-bulb, an electromagnet having one pole within said bulb and provided with a light-emitting surface as described and its helix arranged in a primary circuit-wire, an insulated 95 secondary wire wound around the primary wire throughout its length between lamps, and extending the full length of said primary wire 100 between lamps, and provided within the bulb

- with cathode-terminals substantially as and for the purpose described.
2. An electric lamp comprising a vacuum-bulb, one or more electromagnets each having one pole within said bulb and provided with light-emitting surface as described and its helix arranged in a primary circuit-wire, an insulated secondary wire wound around the primary wire, and extending the full length of said primary wire between lamps, and provided within the bulb with cathode-terminals, one or both of which is coincident with the pole or poles of the electromagnets substantially as and for the purpose described.
- 5 3. An electric X-ray lamp comprising a vacuum-bulb with two cathode-terminals, and one or more electromagnets wrapped to form induction-coils having each one pole within the bulb and provided with a light-emitting surface as described, said induction-coil having a central core, a helix connecting with a primary wire another helix connecting with a secondary wire, the end of said secondary
- 10 15 20
- helix being connected to the core of the induction-coil and forming the cathode-terminal substantially as and for the purpose described.
4. An electric X-ray lamp comprising a vacuum-bulb with two cathode-terminals, one or more electromagnets wrapped to form induction-coils having each one pole within the bulb and provided with a light-emitting surface as described, said induction-coil having a central core, a helix connecting with a primary wire extending between lamps, another helix connecting with a secondary wire wound around the primary wire and extending with it between lamps, the end of said secondary helix being connected to the core of the induction-coil and forming the cathode-terminal substantially as and for the purpose described.
